United States Patent Office

Des. 190,685

Patented June 20, 1961

190,685

SEED PACKAGE

Oliver H. Roskam, Rte. 4, Box 313, Parkville, Mo.

Filed Nov. 14, 1960, Ser. No. 62,826

Term of patent 14 years

(Cl. D58—2)

Fig. 1.

Fig. 2.

Fig. 3.

FIG. 1 is a top plan view of a seed package showing my new design;

FIG. 2 is a side elevational view thereof; and

FIG. 3 is a transverse sectional view thereof taken on line 3—3 of FIG. 1.

I claim:

The ornamental design for a seed package, as shown.
